COMBINATION CURTAIN AND SHADE BRACKET

Filed Sept. 2, 1932 2 Sheets-Sheet 2

UNITED STATES PATENT OFFICE

SAMUEL WILEY SNIDOW, OF ROANOKE, VIRGINIA

COMBINATION CURTAIN AND SHADE BRACKET

Application filed September 2, 1932. Serial No. 631,559.

This invention relates to a bracket for a shade roller and for curtain and drapery rods, the general object of the invention being to provide means whereby the roller and the rods can be attached to a part of the bracket and then the bracket placed in a holder on a window or other support with the parts so arranged that they are firmly held in position.

10 This invention also consists in certain other features of construction and in the combination and arrangement of the several parts to be hereinafter fully described and illustrated in the accompanying drawings and specifically pointed out in the appended claims.

In describing the invention in detail, reference will be had to the accompanying drawings wherein like parts denote like or corresponding parts throughout the several views, 20 and in which:

Figure 1 is a fragmentary view of a window showing the invention in use thereon.

Fig. 2 is a fragmentary top plan view.

Fig. 3 is an end view.

25 Fig. 4 is a view of the holder with the bracket therein.

Fig. 5 is a view of the bracket.

Fig. 6 is a front view of the bracket.

Fig. 7 is a view of one of the rods.

30 Referring to the drawings, the numeral 1 indicates a holder, one of which is fastened to each side of the window trim at the top thereof, as shown in Fig. 1, and each holder is formed with a slot or guideway 2 which 35 tapers downwardly as shown and is adapted to receive the wedge-shaped base part 3 of the bracket 4 which is of plate-like shape preferably formed as shown in Figs. 3 and 5.

The top edge of the bracket is formed with 40 a slight double curve, the concave part being adjacent the outer end of the bracket and terminates in a rounded recess 5. One bracket is provided with a slot 6 for receiving a square trunnion 7 of the shade roller 8 and 45 the other bracket is provided with a round hole for receiving the round trunnion. Each bracket is provided with a pair of holes 9 in its upper part adjacent its inner edge.

Each holder is provided with a cam shaped 50 fin 10 which is spaced slightly outwardly

from the bracket when the same is placed in the holder, as shown.

It will thus be seen that the wedge-shaped base 3 of the bracket will be firmly supported in the holder when the bracket base is 55 placed in the guideway of the holder as the two parts set up a wedging action and the bracket can be easily removed from the holder by pushing the bracket upwardly.

The drapery rod is shown at 11 and the 60 curtain rod at 12, each of these rods having U-shaped ends with the free limb of the U-shaped part entering a hole 9. The rod 12 has a part engaging the recess 5 and the rod 11 rests firmly on the rod 12 and as the 65 bracket is pushed into the holder portions of the free limbs of the U-shaped portion of said rod 11 will engage the fins 10 so that the fins act to bind the rods in position.

70 Thus the curtain rod rests on the point of the brackets and engages the recesses 5 so that the curtain rod is prevented from bending and slipping so that the curtains will remain in the place where they are positioned on the rod. The wedging action between the 75 fins 10 and parts of the curtain rod 11 holds said rod in position against movement and the entire combination is so designed as to be absolutely tight and rigid when properly erected and the parts can be assembled with 80 the curtains and drapes thereon after which the brackets can be placed in the holders which have previously been fastened in place. Any pull on the drapery or curtain is necessarily 85 downwardly and this downward movement tends to pull the brackets more tightly into the holders.

It will of course be understood that but one of the rods can be used when desired.

90 It is thought from the foregoing description that the advantages and novel features of the invention will be readily apparent.

It is to be understood that changes may be made in the construction and in the combination and arrangement of the several parts 95 provided that such changes fall within the scope of the appended claims.

Having thus described my invention, what I claim as new is:—

1. A combination curtain and shade bracket

100

et comprising a holder having a downwardly tapered guideway therein, a bracket having a wedge-shaped base fitting in the guideway and said bracket having openings therein, one of which receives a trunnion of a shade roller and another a part of a curtain or drape rod.

2. A bracket of the class described comprising a holder having a downwardly tapered guideway therein, a bracket member having a wedge-shaped base for fitting in the guideway, said bracket member having openings therein, one of which receives a trunnion of a shade roller and others of which receive end portions of curtain and drape rods, said bracket member having a part of its upper edge forming a seat for a part of one of the rods, with a part of the other rod resting upon a part of the first rod.
3. A bracket of the class described comprising a holder having a downwardly tapered guideway therein, a bracket member having a wedge-shaped base for fitting in the guideway, said bracket member having openings therein, one of which receives a trunnion of a shade roller and others of which receive end portions of curtain and drape rods, said bracket member having a part of its upper edge forming a seat for a part of one of the rods, with a part of the other rod resting upon a part of the first rod, and a cam-shaped part on the holder and engaged by a portion of said other rod to bind said rod in position.

35 In testimony whereof I affix my signature.
SAMUEL WILEY SNIDOW.
